METAL REINFORCEMENT STRUCTURE FOR
HORSESHOES OF ELASTIC MATERIALØistein Harsem, Oslo, Norway, assignor to
Imperator Hestesko Aktieselskap, Tonsberg,
NorwayApplication June 6, 1932, Serial No. 615,733
In Germany June 13, 1931

3 Claims. (Cl. 168—13)

The present invention relates to an improvement in metal reenforcement structures for horse shoes of elastic material, and one object of this invention is to provide such a reenforcement structure of molded material as brass or malleable iron. But the invention is not limited to this, as the structure according to this invention also can very well be manufactured by a forging process.

10 According to this invention the reenforcement structure is given such a shape that it will fulfill all the requirements which are placed on a structure of this type, simultaneously as it will be adapted to anchor itself in the elastic material which forms the horse shoe proper.

15 In order to fulfill these requirements, the reenforcement structure according to this invention has such a shape that, when embedded in the elastic material, it will have upwardly extending projections, which will lie in the plane of that side of the shoe which is to contact with the underside of the hoof of the horse and further have a stepformed shape towards the inside in such a way that the sole of the hoof will rest against soft material.

20 In order to ensure the anchoring of the armour in the rubber material, the reenforcement structure is provided with a number of upwardly extending projections, arranged spaced in relation to each other so that grooves will be formed in the upper surface of the structure, in which rubber straps will be formed, when the structure is molded into the shoe. The said projections are preferably according to this invention arranged off-set in the outward direction in such a way that also vertical straps of rubber may be formed, which adjoin with the above-mentioned straps, crossing transversely over the upper side of the structure.

25 40 In order that this invention may be readily understood and worked, it will in the following be described with reference to the drawing, illustrating a preferred embodiment of the invention.

45 In the drawing

Fig. 1 is a perspective top view of the reenforcement structure and

Fig. 2 is a corresponding perspective view, seen from the underside.

50 The reenforcement structure according to this invention has a main body part 1 of substantial horse shoe shape and adapted to be molded into the interior of the elastic material. On the top of the main body 1, a plurality of projections 3 are arranged in spaced relation to each other,

thereby forming a number of grooves 2, extending transversely across the main body 1. Preferably, the said projections are off-set towards the outside of the main body 1 in such a way that a steplike formation 4 with even surface is formed on the inside of the main body, while a toothlike shape is obtained along the outside of same. Between the teeth, which consist of the outer ends of the projections 3, vertical grooves 8 are formed, which adjoin with 60 the horizontal grooves 2 as above described.

65 For attaching the shoe to the hoof of the horse, nail holes 5 are arranged through the reenforcement structure. These holes are according to this invention arranged through the projections 3, where the thickness of the metal is about twice that of the main structure 1.

70 Furthermore, the structure according to this invention may be provided with a plurality of downwardly extending fingers 7, which may be 75 attached to the inner or outer edge of the main body 1. These fingers are preferably made in such a way that they may be bent down and form hooks which will further serve to ensure the anchoring of the reenforcement structure of 80 the rubber material in the horse shoe.

85 When this reenforcement structure according to this invention has been molded into a rubber horse shoe, a very safe construction of a rubber horse shoe is obtained. The reenforcement 85 structure in itself will be rigidly attached to the nail of the hoof, due to the fact that no elastic material will exist between the upper surface of the projections 3 and the lower surface of the nail of the hoof. Furthermore, continuous rubber straps will be formed transversely to the reenforcement structure through the grooves 2 and 8. Finally, the fingers 7 will form additional security as they in the form of hooks are 90 embedded in the rubber.

95 As will plainly be seen from Fig. 2, the rear parts of the main body 1 may be bent down at 6 and be embedded lower down in the rubber material, whereby that part of the hoof where the nail is too weak to receive fastening nails 100 may rest against the soft rubber, which is very advantageous for the horse.

I claim:

1. A metal reenforcement structure for horse shoes of elastic material, said structure comprising a main body of substantial horse shoe shape and adapted to be moulded into the interior of the elastic material, spaced projections arranged on the top side of the said main body, adapted to project to the surface of the shoe and to form 105

110

abutment for the hoof nail, said projections being offset in a direction outwards from the centerline of the shoe in such a way that the said main body on the inside will have a continuous plane surface, while the said projections on the outside of the main structure will form projecting teeth.

2. A metal reenforcement structure for horse shoes of elastic material, said structure comprising a main body of substantial horse shoe shape and adapted to be moulded into the interior of the elastic material, spaced projections arranged on the top side of the said main body, adapted to project to the surface of the shoe and to form abutment for the hoof nail, said projections being offset in a direction outwards from the centerline of the shoe in such a way that the said main body on the inside will have a continuous plane surface, while the said projections on the outside of the main structure will form projecting teeth.

3. A metal reenforcement structure for horse shoes of elastic material, said structure comprising a main body of substantial horse shoe shape and adapted to be moulded into the interior of the elastic material, spaced projections arranged on the top side of the said main body, adapted to project to the surface of the shoe and to form abutment for the hoof nail, said projections being offset in a direction outwards from the centerline of the shoe in such a way that the said main body on the inside will have a continuous plane surface, while the said projections on the outside of the main structure will form projecting teeth, and a plurality of fingers, attached to the opposite side of the main body and adapted to form hooks for securing the structure in the elastic material.
